[Term of Patent 3½ years.]

CASE L.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern intended especially for perforated board; and it consists in the peculiar configuration and ornamentation of the motto, as shown in the accompanying illustration.

The motto forming the base of this design is "He leadeth me." The form of the letters

composing the several words is clearly shown in the accompanying illustration, the capitals being the principal feature in this part of the design.

The ornamentation in this design consists of a tracery of "Grecian key," and scroll-work interlaced with the motto, with a crook and lamb as emblems, as shown in the accompanying illustration.

I claim—

The design for embroidery-patterns, herein described, consisting of the motto "He leadeth me," in form and ornamentation as shown in the accompanying illustration.

EMIL CRISAND.
